Inventor:

Arthur F. Durand

UNITED STATES PATENT OFFICE.

ARTHUR F. DURAND, OF CHICAGO, ILLINOIS.

MOTOR BOAT.

Application filed January 5, 1927. Serial No. 159,085.

This invention relates to motor boats, and more particularly to those adapted for high speed.

An object of the invention is to provide a motor boat having a multiple-keel hull, the bottom of which is of the inverted W-type, having parallel, vertical sides, being composed in effect of two transposed, longitudinal halves of one boat disposed at opposite sides of another boat, thus providing three keels with the two inverted V bottoms between said keels, forming in effect an inverted W-bottom boat of the so-called sea-sled type.

Another object is to provide an air propelled boat in which the air propeller is disposed as low down as possible at the stern of the boat, to more nearly approximate the propulsion by an ordinary water propeller, and to thereby render the boat more stable and less liable to roll over.

Another object is to provide an air propeller having a guard therefor, arranged and constructed to prevent injury to persons in or out of the boat, as well as to prevent the water from striking the air propeller when the boat is running, especially in a heavy sea.

Another object is to provide a motor boat in which the engine weight is disposed as far forward in the bow of the boat as possible, in which the propeller is mounted directly on the rear end of the long engine shaft which extends from the engine to the stern of the boat, so that under high speed the momentum will tend to keep the boat head on, like an arrow weighted at its head, and in which the said propeller is preferably an air propeller, for with the engine set forward in the bow of the boat the long engine shaft does not have to be tilted up very much to position its rear end portion just above the stern of the boat, whereby substantially only one half of the air propeller extends above the stern of the boat, the lower half being immediately behind the stern.

It is also an object to provide certain details and features of construction tending to increase the general efficiency and the desirability of motor boats of this particular character.

To the foregoing and other useful ends, the invention consists in the matters herein-

after set forth and claimed, and shown in the accompanying drawings, in which,—

Fig. 1 is a plan of a motor boat embodying the principles of the invention.

Fig. 2 is a side elevation of said boat, showing the same at rest in the water.

Fig. 3 is a transverse section on line 3—3 in Fig. 1.

Fig. 4 is a transverse section on line 4—4 in Fig. 1.

Fig. 5 is a transverse section on line 5—5 in Fig. 1.

Fig. 6 is a view similar to Fig. 2, but showing the boat moving at high speed in the water.

As thus illustrated, and looking at Fig. 1, it will be seen that the hull of the boat is in effect composed of two narrow boats, one narrow boat having been divided longitudinally, and the two halves thus formed having been transposed and placed at opposite sides of the other narrow boat, the dotted lines 75 1 and 2 indicating the sides of the two halves which have been transposed, and the dotted lines 3 and 4 indicating the sides of the narrow boat which was, so to speak, left intact, and which serves as the central portion of the hull of the boat. In other words, a boat of the so-called sea-sled type, but having three keels, instead of two, is in effect made by taking two narrow boats of good lines, each with a tapered and well formed bow and a stern of any suitable formation, and each with a central keel, and, figuratively speaking, splitting one boat centrally and longitudinally to form two longitudinal halves, which halves are then transposed and arranged at opposite sides of the other narrow boat. Then the central boat and the two lateral halves are merged together by cutting down their adjacent sides, and by filling in between their bow portions 95 and their stern portions so that cross sections of the entire boat structure will be of the character shown in Figs. 3, 4 and 5 of the drawings. This forms what may be called an inverted W-bottom, or a double inverted V bottom, as shown in these cross sections, with the three equidistant keels 5, 6 and 7, as shown. The cross section on line 3—3 in Fig. 1 shows the tapering, center bow portion 8, and shows the tapering, lateral bow portions 9, as well, the two transposed halves

of the said longitudinally divided boat being closed at their outer sides by parallel, vertical walls 10 in the manner shown, whereby the boat has vertical, parallel sides that, like any 5 sea-sled type boat, tend to make the boat a dry one in a rough sea. Farther back, at a section on line 4—4 in Fig. 1, as shown in Fig. 4 of the drawings, the interior of the boat becomes more roomy, as the connections 10 11 between the adjacent sides of the said middle boat hull and the two outer transposed halves are lower down, of course, than they are at 12 in Fig. 3 of the drawings. The section at line 5—5 in Fig. 1, as shown in Fig. 15 5 of the drawings, brings the connections between the middle boat hull and the two outer halves somewhat higher, as at 13, so that the somewhat narrow stern portion 14 of the middle boat-hull section is well defined in cross section, and the two inverted V-spaces 20 are much higher.

In this way a sea-sled type boat is provided comprising a longitudinal, central boat-hull section with tapered bow and suitable stern 25 formation, and comprising transposed, longitudinal boat-hull halves forming lateral or outside boat-hull sections, with the three boat-hull sections connected at their adjacent sides and merged into one boat hull having 30 three equidistant, parallel keels, and having parallel and vertical sides which terminate at their lower edges in the two outer keels of the boat. This, as shown, gives the boat full depth at the longitudinal center thereof, over 35 the middle keel, but without reducing the height of the inverted V-spaces between the keels. In the ordinary sea sled, for example, composed merely of two transposed, longitudinal halves of one boat hull, and having 40 only two keels, one at the lower edge of each flat side of the boat, the longitudinal center of the boat must be cut down considerably, so that the inverted V-space between the keels is reduced considerably in height, in order to 45 obtain room in the boat for the engine and passengers and other things. However, with the construction shown and described, which is illustrative of one form of the invention, the two inverted V-spaces between the keels 50 may be of any desired height which in practice will give the best results, and at the same time the longitudinal, central portion of the boat may be of full depth, as the space here may extend clear down to the center or middle keel of the boat. In Figs. 2 and 6, for 55 example, the dotted line 15 represents the connection 11, 12 and 13, as shown in Figs. 3, 4 and 5, and shows that this connection is low down for the greater portion of the 60 length of the boat, but is higher up in the bow and stern portions of the boat, as illustrated in the cross sections, Figs. 3, 4 and 5 of the drawings.

When the boat is running at full speed, it 65 preferably assumes about the position shown

in Fig. 6 of the drawings, and for this purpose the keels are made deeper at the bow of the boat than they are at the stern, so that the keels will be about horizontal when the boat is running at full speed, thus keeping 70 the keels in the water at the bow, notwithstanding that the bow rises when the boat is going at full speed.

The boat may be propelled by any suitable power, but is well adapted for propulsion by 75 an air propeller, and for this purpose the engine 16 is preferably mounted as far forward in the bow of the boat as possible, and the long, straight engine shaft 17 is tilted upward just enough to enable it to extend over the 80 stern of the boat and be supported in a bearing 18 mounted on the stern in any suitable or desired manner. The air propeller 19 is of any suitable or desired character, and is secured to the end of the shaft 17 immediately 85 in rear of the stern of the boat, and with this arrangement only about half of the propeller extends above the stern of the boat, and the other half is immediately behind the stern, as shown. A sheet-metal, cylindrical hood 90 or guard is mounted on the stern of the boat to enclose the air propeller, this guard being open at its front 21 and provided with a crating or grill work 22 to prevent access of persons or things to the revolving propeller. It 95 will be seen that the under portion of the guard or hood 20 is at the water line, when the boat is standing still, as in Fig. 2, but when the boat is running at high speed the bottom portion of this guard 20 is depressed 100 into the water somewhat; but with the boat running at high speed the water will not enter, and the blast of air from the propeller is low down and behind the stern of the boat and against the water.

The rudder 23 is preferably hinged centrally to the guard 20, as shown, and extends into the water a distance, so that it is both an air and a water rudder, and is controlled by the steering wheel 24 through the medium of 110 any suitable connection (not shown) to steer the boat to the right or the left at will. With this construction, the weight of the engine and of the propeller is all placed low down in the boat, so that the boat is stable and seaworthy and is not liable to roll over. Some boats having air propellers are made top-heavy, because of the high position of the air propeller and the engine, and are not adapted for anything but smooth water. However, 115 with the construction shown and described, which is illustrative of one form of the invention, the boat, while driven by an air propeller, is nevertheless capable of safe and comfortable travel in rough water. The weight of the engine in the bow of the boat keeps it head on, as against wind or waves, much like an arrow weighted at its head, and the triple bow and keel and bottom formation 120 cut the water and prevent pounding, which 125 130

is one trouble with flat-bottomed boats, and the flat, straight, parallel sides of the boat, which are characteristic of the sea-sled type of boat, do not throw the water, but make the boat a dry one in rough water.

In order that the propeller may have plenty of air ahead of it, and may breathe, so to speak, the stern portion of the boat is preferably grooved or cut down or recessed, as shown at 25 in Fig. 5, and as indicated by the dotted line 26 in Fig. 6 of the drawings. In this way the air propeller is kept working at full atmospheric pressure, and is not pocketed, so to speak, behind the stern of the boat.

Thus, in plan view, as shown in Fig. 1, the boat is rectangular in shape, with straight parallel sides and with straight transverse ends, or at least with a blunt bow and stern. The middle hull section, indicated by the lines 3 and 4, has a tapered bow, and this hull section is also tapered toward the stern, and the outer, transposed boat-hull halves are of similar formation, so that the triple bow is formed by three forwardly tapered bows, and the triple stern is formed by three rearwardly tapered stern portions. The shaft 17 is tilted upward just enough, of course, to enable the shaft to extend over the stern of the boat, the engine being placed forward for this purpose, as well as to give the boat weight in the bow thereof.

Thus the boat has a triple tapered bow, and also a triple tapered stern, together with a triple keel bottom, each keel connecting a bow with a stern. The triple bow is decked over, and the triple stern is likewise decked over, thus providing a continuous deck from the blunt bow to the blunt stern, with space below the decking between the three bows, and with space under the decking between the three sterns, in the manner shown. The boat is at least as wide at the bottom as it is at the top thereof, throughout the length thereof, so that the sides present no overhang anywhere throughout the length thereof, so far as the actual hull structure is concerned.

Without disclaiming anything, and without prejudice to any novelty disclosed, what I claim as my invention is:

1. A motor boat of the sea-sled type, formed in effect by a longitudinal and central boat-hull section having a central keel and a tapered bow, disposed between two transposed longitudinal boat-hull halves forming lateral boat-hull sections, with the three sections merged together at their adjacent sides, with the straight parallel sides of the boat as a whole terminating at their lower edges in keels which are parallel with said central keel, the three sections of the boat being of the same length, whereby in plan the boat as a whole is rectangular with parallel sides and a blunt bow and stern.

2. A structure as specified in claim 1, said

outer sides of the boat as a whole being vertical, and the spaces between said keels being of inverted V-formation of minimum height midway between the bow and stern of the boat, and of greater height at the bow and stern, providing an inverted W-bottom for the boat.

3. A structure as specified in claim 1, the spaces between said keels being of inverted V-formation, of less height midway between the bow and stern of the boat and of greater height at the bow and stern, forming an inverted W-bottom for the boat.

4. A seal-sled type boat comprising three equidistant parallel keels, with inverted V-spaces between said keels, and vertical parallel sides for the boat, said sides terminating at their lower edges in the two outer keels, and the boat in plan view being rectangular with parallel sides and a blunt bow and stern.

5. A structure as specified in claim 4, in combination with an engine in said boat, an air propeller mounted on the stern of the boat, and a shaft connecting the engine with the propeller, in the vertical plane of the middle keel of the boat, with the engine arranged forward to minimize the upward tilt necessary for the shaft to extend over the stern of the boat.

6. A structure as specified in claim 4, in combination with an engine in said boat, an air propeller mounted on the stern of the boat, a shaft connecting the engine with the propeller, in the vertical plane of the middle keel of the boat, with the engine arranged forward to minimize the upward tilt necessary for the shaft to extend over the stern of the boat, the blades of the propeller revolving close to the water immediately behind the stern of the boat, and a guard having a portion thereof extending under the propeller to keep the water from striking the propeller when the boat is in motion.

7. A motor boat comprising a boat hull, an engine mounted forward in said hull, an air propeller mounted at the stern of the boat, disposed so low down that the propeller blades revolve immediately behind the stern of the boat, so that substantially only the upper half of the propeller extends above the stern of the hull, and an engine shaft connecting the engine to said propeller, the stern of the boat being formed with a cavity in the upper portion to freely feed air to the blades when in their lower position.

8. A structure as specified in claim 7, and a guard extending over and under said propeller, to prevent injury to persons and things by said propeller, and to prevent the water from striking the propeller when the boat is in motion.

9. A motor boat having a plurality of parallel keels which are deeper at the bow of the boat than at the stern thereof, thereby to keep the keels in the water when the bow

rises, the forward portions of the keels all having flat vertical side surfaces and each keel terminating at opposite ends in a tapered bow and a tapered stern, with the outer side of the boat flat and straight and vertically disposed above the two water keels.

10. A motor boat provided with an air propeller at the stern thereof, disposed so low down that the blades of the propeller revolve immediately behind the stern of the boat, so that substantially only the upper half of the propeller extends above the stern of the hull, and motive power for rotating said air propeller, the said propeller being close to the water behind the stern of the boat, the stern of the boat being formed with a cavity in the upper portion to freely feed air to the blades when in their lower position.

11. A structure as specified in claim 10, in combination with a guard enclosing the propeller and open at front and rear thereof, the guard having a portion extending under the propeller and serving to prevent the water from striking the propeller when the boat is in motion.

12. A structure as specified in claim 10, in combination with a guard enclosing the propeller and open at front and rear thereof, the guard having a portion extending under the propeller and serving to prevent the water from striking the propeller when the boat is in motion, and a combined air and water rudder hinged on said guard in the vertical plane of the axis of said propeller.

13. A structure as specified in claim 10, the boat hull being recessed in the stern portion thereof to feed air downwardly to the blades of the propeller.

14. A boat having a triple bow, a triple stern, each bow and stern tapered, and a triple keel bottom, each keel connecting a stern with a bow, the three keels being parallel, and there being space upwardly tapered in cross section between the keels throughout the length thereof, each outer bow and stern being straight on its outer side and tapered on its inner side.

15. A structure as specified in claim 14, the triple bow being decked over, and the triple stern being decked over, so that the boat has a continuous deck from bow to stern thereof.

16. A structure as specified in claim 14, the triple bow being decked over, and the triple stern being decked over, so that the boat has a continuous deck from bow to stern thereof, 55 the sides of the boat being straight and parallel and terminating at their lower edges in the two outer keels, the bottom of the boat being at least as wide as the distance between the upper edges of the side walls throughout 60 the length thereof.

17. A boat having a triple bow and straight flat sides, the three bows being the same in depth, each outer bow being straight and flat on the outside and tapered on the inside 65 thereof, so that the front edge of each outer bow is in the plane of the side of the boat, the middle bow being tapered on each side thereof, and the spaces between the bows being decked over to in effect form a single bow 70 when viewed from above.

18. A boat as specified in claim 17, the sides of the boat being straight and parallel throughout the length thereof, and the beam 75 of the boat at top being no greater than the beam at the bottom.

19. A boat as specified in claim 17, comprising a stern of substantially the same width or beam as the beam at midships and 80 at the bow thereof.

20. A boat as specified in claim 17, each bow having a keel extending rearward a distance, said keels being parallel, and there being spaces between the keels, each space in cross section tapering upwardly into the hull of the 85 boat.

21. A boat as specified in claim 17, the three bows being the same in length and in transverse alinement.

22. A boat having a triple bow, each outer 90 bow being straight and flat on the outside and tapered on the inside thereof, the middle bow being tapered on each side thereof, and the spaces between the bows being decked over 95 to in effect form a single bow when viewed from above, the sides of the boat being flat and parallel from bow to stern, and the two outer keels forming lower edges of said flat sides.

Specification signed this 31st day of Dec., 100
1926.

ARTHUR F. DURAND.
